APPARATUS FOR REDUCING THE EXPANSION OF FLUIDS

Jose Maria Domingo Grossi, Buenos Aires,
ArgentinaApplication February 25, 1943. Serial No. 477,151
In Argentina January 16, 1943

2 Claims.

(Cl. 138—41)

This invention refers to a new apparatus having for its object to produce a reduction of the expansion of the fluids, which apparatus is particularly intended for substituting the valve presently used in electric refrigerators and other refrigerating apparatuses, for controlling the feeding of the freezing fluid, which valve is placed between the feeding source thereof and the freezing coil.

The various types of valve used up to the present for the purpose, despite that their working is satisfactory, considered in a general way, comprise such complicated devices that very easily get out of proper working conditions and require to be repaired at short intervals or some of the parts replaced owing to breakage or excessive wear. One example that confirms the above statement is the metallic bellows with which the existing valves are provided, a part that very readily breaks down and causes leakage of the refrigerating fluid; they also comprise springs which, upon suffering any minimum alteration, fail to properly control the passage of the refrigerating fluid through the valve and thus cause a variation on the normal distribution in the freezing coil.

Another trouble with the existing valves resides in the fact that they are provided with a thermostatic bulb connected with the exit end of the freezing coil, and when the compressor is started there is a delay of some minutes before the freezing of the exit end of the coil connected to the bulb takes place; it happens in the meantime that the bulb allows a certain amount of the refrigerating fluid to pass, a failure that sometime causes the pressure to be raised very much above the normal and in many cases there result serious damages to the valve and even to the compressor.

There is already in use a type of valve which is provided with a long pipe of small diameter, wound in the shape of a spiral, intended to produce a reduction of the expansion of the refrigerating fluid. The very serious trouble with this type of valve is, that owing to the various technical reasons which prevent it, the pipe cannot be opened for thoroughly cleaning the incrustations which tend to seal it, and this failure causes a great drawback on the operation of the refrigerating apparatus. Sometimes the operation thereof is stopped thereby.

Finally, the operation of every known valve offers the risk of permitting a return of the refrigerating fluid to the compressor with the corresponding danger of blows delivered by the pistons against the head of the compressor cylinders, 55

an accident which generally destroys the joints or the valves.

The above and other troubles well known to those skilled in the art are readily overcome with the use of the apparatus forming the subject matter of this invention. There is no metallic bellows, neither springs comprised in it; there is no thermostatic bulb or regulating needles for the passage of the refrigerating fluid, parts that are always subject to wearing out and breakage.

The apparatus is constituted by two tubular parts only, one inside the other, it being its own particular and constructive novel features that will be hereinafter fully described, which enable the apparatus to advantageously substitute the existing valves both on the technical and economical grounds.

The installation of the apparatus is very simple and can be carried out in a very short time. It requires only two connections; one for admission and the other for discharge. The existing valves require, some of them, up to five connections.

The apparatus is provided with a chamber for cooling the liquid refrigerating fluid that arrives from the source that feeds it, and therefore, when the liquid afterwards passes through the expansion reducing spiral, there takes place a fall on the pressure of the refrigerator, an arrangement that affords the maximum output.

It is to be noted that the apparatus can be employed in refrigerators or the like provided with automatic control for the temperature, as well as in those refrigerators having a low pressure automatic control.

As the apparatus does not comprise parts that are likely to be damaged or become destroyed, it will be evident that, besides its advantages as to low cost and efficiency, it is of unlimited duration. It can be taken to pieces very easily whenever it is required and during the trials that have been made, its advantages have been made clearly evident.

In order that the invention may be understood and easily carried into practice, a full description thereof will now be given with reference to the accompanying drawings wherein the same numerals of reference indicate similar or equivalent parts all through the various figures.

50 In the drawings:

Fig. 1 is a view of the outside of the apparatus.

Fig. 2 is a lengthwise section showing the inside thereof.

Fig. 3 is a view of the tubular member which forms the freezing chamber and the expansion

reducing member formed directly in the exterior face thereof.

Fig. 4 is a front view of the bottom of the member shown in the former figure.

Fig. 5 shows the wrappage wherein is tightly fitted the other tubular member shown in Figure 3, so disposed that when the latter is forced inside the former, the inner surface of the wrapper and the outer surface of the freezing chamber will form between them a long helical tube for reducing the expansion of the refrigerating fluid on its passage therethrough.

In the drawings it has been indicated with 1 the external wrapper whose end 2 is open for receiving the other tubular member 3 which constitutes the freezing chamber and the expansion reducing member.

The other end 4 of the wrapper 1 is also open for being connected to the freezing coil of the refrigerator or the like (not shown). For facilitating this connection, the end 4 is externally threaded as shown in 5 for receiving a nut 6.

The tubular member has its admission end 7 open for being connected to the source that feeds the refrigerating fluid; it is externally threaded as shown in 8 and carries a nut 9.

The other end or bottom 10 of the tubular member 3 is closed and is provided with an external slot 11.

The numeral 12 indicates the freezing chamber formed in the interior of the tubular member 3, the chamber being provided at its upper part with an exhaust perforation or port 13 placed near the admission opening thereof.

The external surface of the tubular member 3, starting at the exit opening 13 and up to the closed end 10, carries a helical slot 14 which provides a long tubular helical passage when the said member is fitted inside the wrapper 1, through which passage circulates the refrigerating fluid under reduced expansion.

A metallic mesh filter 15 is placed within the admission end 7 of the tubular member 3 for preventing the entrance of any foreign matter into the chamber 12 and to settle therein, sealing at some point the slot 14.

The operation of the apparatus is readily appreciated in the above description and in the drawings.

However, a brief description of same will be given hereafter, in order to clear up any doubt that may eventually still remain.

After the apparatus has been connected, its admission 7 to the source feeding the refrigerating fluid and the exit opening 4 to the freezing coil, the compressor is started.

The liquid refrigerating fluid penetrates through the admission 7 and is strained by the filter 15. After leaving the filter it starts its travel through the freezing chamber 12 towards the exit 13 through which it goes out of the chamber, penetrating in the helical tubular passage formed by the slot 14, through which it travels under reduced expansion at a very low temperature and arrives at the end 10 where, passing through the slot 11, comes to the exit end 4 of the apparatus and goes into the freezing coil.

It is to be clearly understood that despite the fact that this apparatus is particularly intended for being applied to refrigerating chambers, its use must not be considered as limited to that adaptation because, as it is apparent, other uses may be made thereof or be adapted to other devices. Also, that in carrying the invention into use, constructional details might be changed so far as the scope of the invention as defined by the following claims is maintained.

What I claim is:

1. A device of the character described comprising a tubular casing having an internal shoulder near one end thereof, a tubular liner telescoped within the casing abutting said shoulder and having a spiral groove in its periphery cooperating with the inner surface of the casing to form a spiral passageway terminating at one end at said shoulder, a port extending through the wall of the liner and communicating with the opposite end of the spiral passageway, a plug closing the end of the tubular liner which is adjacent to the shoulder and provided with a groove placing one end of the spiral passageway in communication with one end portion of the casing, and means at the opposite end of the tubular liner to facilitate the attachment of a pipe thereto.

2. A device as claimed in claim 1, in which a substantially cupped shape screen extends into the liner from the last-mentioned end thereof and terminates adjacent to said port.

JOSE MARIA DOMINGO GROSSI.
